HOUSEHOLD RACK FOR HOLDING SHOES

George H. Hackathorn, East Liverpool, Ohio, assignor of one-half to David F. McConnell, East Liverpool, Ohio

Filed Nov. 9, 1959, Ser. No. 58,257

Term of patent 14 years

(Cl. D33—3)

Figure 1 is a perspective view of a household rack for holding shoes, showing my new design; and

Fig. 2 is a side elevational view thereof.

I claim:

The ornamental design for a household rack for holding shoes, as shown.
